CABINET DOOR FASTENING DEVICE

Edwin C. Worthley, Minneapolis, Minn.

Application May 3, 1943, Serial No. 485,472

3 Claims. (Cl. 292—228)

My invention belongs to the cabinet art and pertains to an improved fastening device or apparatus for hinged cabinet doors.

While the invention is adapted for use in connection with cabinets of many different designs and for many different purposes, it was primarily designed for use in connection with cabinets for portable motor generator sets, and, when so used, serves to maintain a constant closing pressure on the hinged cabinet door so long as the door is closed, thereby preventing accidental opening of the door, even if it be not positively locked closed, and holding the door against vibratory movement or rattling under transportation vibration. In the preferred embodiment of the invention herein illustrated, this is accomplished by hinging or pivotally anchoring to the cabinet immediately adjacent one outside edge of the door opening thereof a flange or wing which is yieldingly biased to move toward a position wherein it overlaps the door opening or rests against the outside of the door when the door is closed. Preferably, and according to the present illustration, the biasing of the flange or wing is provided through the medium of a suitable spring or springs, and novel means is provided for holding the flange or wing in an outwardly-extended inoperative position. As a still further feature of the invention, I preferably provide the cabinet door with one or more lock-receiving anchoring devices and provide the flange or wing with a notch or notches to receive such anchoring device or devices. The above and numerous other objects, advantages, and important features of the invention will be made apparent from the following specification, claims, and appended drawings.

In the accompanying drawings, like characters indicate like parts throughout the several views.

Referring to the drawings:

Fig. 1 is a perspective view, with the door closed, of a cabinet involving the invention;

Fig. 2 is a perspective view similar to Fig. 1 and showing the cabinet door and fastening flange or wing in their open positions;

Fig. 3 is a greatly enlarged fragmentary sectional view taken on the line 3—3 of Fig. 2; and

Fig. 4 is a fragmentary detail sectional view taken on the line 4—4 of Fig. 3.

The cabinet illustrated is, as previously indicated, designed to house portable motor generator sets such as are used for field lighting and power purposes, and such a motor generator set is indicated by dotted lines in Fig. 2. The particular cabinet illustrated involves a rectangular wooden framework 5 cut out to receive wooden top, bot-

tom, and side panels 6. The front of the cabinet is primarily open, but is provided with a hinged door 7. All edges of the cabinet are shown as covered by cross-sectionally rounded reinforcing strips 8. The door 7 is shown as being in the nature of a wooden panel that is received in the door opening and which is provided at its edges with metal reinforcing strips 9 that project beyond the edges of the door panel and overlap the outer edge portions of the door opening when the door is closed. This door 7 is hinged to the cabinet at its bottom edge portion by means of suitable hinges 10. The bottom of the cabinet is provided adjacent its opposite side portions with forwardly and rearwardly extending skidways 11, which are adapted to slidably engage runners or skids 12 of a platform 13. In practice, a motor generator set such as indicated by dotted lines in Fig. 2 will be mounted fast on the platform 13 and the platform and motor generator set will be slid as a unit into the cabinet for storage or transportation purposes, and will be slid out onto the opened cover 7 during operating periods of the motor generator unit. Preferably, a drawer 14 for tools and accessories is slidably mounted in the upper portion of the casing on suitable rails 15 and is provided with a depending handle 16 for withdrawing the same slidably through the opened front of the casing.

The hinged wing or flange of the preferred embodiment of the invention illustrated, indicated by 17, is somewhat wider than the door opening in the cabinet and is pivotally connected to an anchoring flange 18 on an axis parallel to but spaced slightly above the upper edge of the door opening at 19. In fact, the flanges or wings 17 and 18 together form a long hinge having a free flange or wing 17 and an anchored flange 18. The anchoring flange 18 is rounded to conform to the rounded upper front corner of the cabinet and is anchored thereto by screws or the like 20. As a means for yieldingly biasing the flange or wing 17 to move to its closed or door opening overlapping position, a pair of coil torsion springs 21 are disposed over the pivot pin of the hinge and have their opposite ends overlapping opposite flanges or wings 17 and 18. To facilitate raising or opening of the wing 17 against the action of the springs 21, I preferably equip the wings 17 with a suitable handle 22.

While the spring-pressed flange or wing 17 of the invention will exert sufficient resilient closing pressure against the upper edge portion of the door 7 to prevent accidental opening thereof, it is often desirable to lock the cabinet closed to pro-

tect the motor generator set or the like against tampering or theft, and for this purpose I preferably provide the door 7 with apertured staple-like fastening devices 23, and provide receiving apertures 24 therefor in the flange 17. When the flange 17 is closed over the fastening devices 23 as shown in Fig. 1, suitable padlocks may be inserted through the apertured fastening devices 23 just as in the case of a conventional lock hasp.

As a means for holding the flange or wing 17 in its raised inoperative position against the action of the springs 21, I provide a mechanism comprising a headed plunger 25, a coil compression spring 26, and a channel-shaped casing 27, see Figs. 3 and 4. The plunger 25 works slidably through a drilled hole 28 in the upper front corner member of the frame 5 and reinforcing plate 8 therefor and the head 25a thereof works slidably in the pressed metal channel 27, which latter is anchored to the top panel of the cabinet by anchoring screws 29 and has a closed inner end 30. The coil spring 26 is interposed between the closed inner end 30 of the channel 27 and the head 25a of the plunger, and has sufficient force and is of sufficient length to push the plunger outwardly to the position thereof shown by dotted lines in Fig. 3, when the flange 17 is raised to its open position. Now, when it is desired to retain the flange 17 in its raised inoperative position without exertion of hand pressure, the operator merely pulls on the partially projected plunger 25 and slides the same out to its full line position of Fig. 3, wherein it will support the flange 17 against the action of the springs 21. Usually the plunger 25 will be left in this fully extended full line position so long as the door 7 is open. However, when the door is closed and it is desired to render the flange 17 operative thereon, the operator merely lifts upward slightly on the flange 17 to release the plunger of its pressure and then pushes the plunger back to its partially retracted dotted line position of Fig. 3, after which the closing pressure of the spring-pressed flange 17 will complete the retraction of the plunger 25 against the action of its spring 26 by cam action.

What I claim is:

1. In a cabinet having a door opening and an outwardly hinged door for said opening, a wing-like flange pivoted to the cabinet adjacent the edge of the opening opposite the door hinge and

on an axis parallel to the axis of the door hinge, yielding means for biasing the wing-like flange to move over a portion of the door opening and against the outside of the closed door to hold 5 against accidental opening movements and rattling vibrations; and a plunger working slidably through the cabinet between an edge of the door opening and the pivot point of said wing flange, said plunger being free to slide longitudinally 10 from a retracted position substantially flush with the outer wall of the cabinet to an extended position wherein it will support the wing flange in an inoperative position against the closing pressure exerted by its cooperating biasing means, and 15 yielding means tending to project said plunger.

2. In a cabinet having a door opening, an outwardly opening door hinged thereto adjacent one edge of the door opening, a wing flange hinged to the cabinet adjacent an outer edge of the door opening opposite the hinge axis of the door and on an axis parallel to the hinge axis of the door and adjacent edge of the door opening, said wing flange extending substantially the length of 20 the adjacent edge of the door opening and being of sufficient width to overlap the adjacent edge of the door opening and edge portion of the door when the door is closed, yielding means biasing the wing flange to move into engagement with the outer face of the door and hold the same 25 against accidental opening and vibratory movements and a plunger working slidably through the cabinet toward an edge of the door opening and the axis of the wing flange, said plunger being free to slide longitudinally from a retracted position wherein its outer end is substantially 30 flush with the outside of the cabinet to an extended position wherein it will underlie and support the wing flange in an inoperative open position against closing pressure exerted by its cooperating biasing means.

3. The structure defined in claim 2, in further combination with yielding means tending to partially project the plunger to a position where it can be gripped by the fingers of the operator but from which it is capable of being further retracted by cam action of the wing flange thereon under the action of its biasing means.

EDWIN C. WORTHLEY.
